UNITED STATES PATENT OFFICE

JAMES KANTOR, OF CHICAGO, ILLINOIS, ASSIGNOR TO THE LIQUID CARBONIC CORPORATION, OF CHICAGO, ILLINOIS

FILLING MECHANISM

Application filed March 14, 1927. Serial No. 175,316.

My invention relates to improvements in filling mechanisms of the type which are adapted to dispose measured amounts of liquid, such as syrup, in bottles, and it consists in the combinations, constructions, and arrangements herein described and claimed.

An object of my invention is to provide a filling mechanism in which the capacity of the measuring means may be varied to the slightest fraction of an ounce.

A further object of my invention is to provide a device of the type described by means of which desired quantities of the liquid may be disposed in each bottle, irrespective of the temperature effect upon the liquid or the density of the liquid used.

A further object of my invention is to provide a device of the type described which may be readily substituted for the old type of measuring means.

A further object of my invention is to provide a device of the type described which is simple in construction, durable and efficient for the purpose intended.

Other objects and advantages will appear in the following specification, and the novel features of the invention will be particularly pointed out in the appended claims.

My invention is illustrated in the accompanying drawings, forming part of this application, in which

Figure 1 is a side elevation of my device, portions thereof being shown in section,

Figure 2 is a plan view of my device, and

Figure 3 is a sectional view of a portion of my device.

In carrying out my invention, I provide a liquid tank 1 having one or more openings 2 in the bottom wall 3 thereof. A guide or supporting rod 4 is slidably disposed in a bushing 5 which extends through the bottom 3 of the tank 1. A bell 6 for receiving the neck of a bottle, which is indicated at 7, is rigidly mounted upon the lower end of the guide rod 4. A compression spring 8 is disposed concentric with the guide rod 4 and bears at one end upon the bell 6 and at the other end upon the bushing 5. A support 9 in the form of a triangular block is secured to the upper end of the guide rod 4 by means

of a nut 10. A measuring cup which is composed of a cylindrical body portion 11 and a bottom portion 12 having its inner wall tapering downwardly toward the center thereof is disposed in the tank 1 in alignment with the opening 2. The measuring cup is so constructed that the cylindrical body portion 11 may be moved with respect to the bottom portion 12 and still prevent a liquid from passing from the cup between the body portion 11 and the bottom portion 12. The bottom portion 12 is provided with a groove 13 for receiving one end of a fork 14. The other end of the fork 14 is rigidly secured to a supporting rod 15 which extends upwardly through the support 9 and is rigidly secured thereto by a nut 16. In this manner, the bottom portion 12 is rigidly held against movement with respect to the support 9.

A sleeve 17, rigidly secured at 18 to the body portion 11, is disposed concentric with the supporting rod 15, and is movable thereupon. The upper end of the sleeve 17 is rigidly secured to an arm 19 which extends outwardly at right angles therefrom and is provided with a post 20. The post 20 is provided with threads 21 which are adapted to receive the threads of an internally threaded collar 22. The post 20 is also provided with a reduced threaded portion 23 which is adapted to receive the internal threads of an indicating cylinder 24. The indicating cylinder 24 is provided with indicating lines 25 circumferentially disposed thereupon. A lock nut 26 is disposed upon the reduced portion 23 for holding the indicating cylinder 24 in any adjusted position.

The collar 22 is held against longitudinal displacement by a forked retaining plate 27, the forked end 28 of which is receivable in an annular groove 29 of the collar. The forked retaining plate 27 is rigidly held between the support 9 and the nut 10. An indicating line or groove 30 is disposed in the forked retaining member 27, see Figure 2. An indicating wheel 31 is disposed concentric with the collar 22 and is provided with indicating lines 32 which are equally spaced thereupon and extend inwardly from the peripheral edge thereof. An adjusting nut 33

80

85

90

95

100

is provided with an internally threaded portion 34 which is adapted to receive external threads 35 upon the collar 22. A set screw 36 extends through the adjusting nut 33 and is in engagement with the indicating wheel 31. The set screw 36 acts as a key to prevent rotation of the nut 33, and locks the indicating wheel 31 against rotation with respect to the adjusting nut 33.

10 A liquid valve tube 37 is rigidly secured to the tank 1 and extends upwardly through the opening 2 in the bottom 3 to a point above the level of a liquid 38. This liquid is kept at the predetermined level by means not shown. The lower portion of the liquid valve tube 37 extends downwardly through the bell 6 and is adapted to enter the bottle 7. A drip check 39 is adjustably secured to the support 9 by the nut 16 and is positioned in alignment with the liquid valve tube 37.

15 The check 39 may be moved into and out of alignment with the tube 37 for a purpose hereinafter described.

20 From the foregoing description of the various parts of the device, the operation thereof may be readily understood. As stated heretofore the liquid 38 maintains approximately the level shown in Figure 1, irrespective of the speed at which the liquid passes 25 from the tank.

25 Let us assume that the operator wishes to place four ounces of the liquid 38 into the bottle 7. The measuring cup, as shown in Figures 1 and 2, is set to receive just four ounces 30 of the liquid. As the bottle 7 is moved upwardly by means not shown the bottle engages with the bell 6, thus raising the bell, the guide rod 4, the support 9, and the measuring cup upwardly to a point where the upper extremity of the measuring cup will be 35 positioned above the level of the liquid 38. During this upward movement of the measuring cup, the full capacity which is four ounces of the liquid will be received in the measuring cup. When the measuring cup 40 has reached its uppermost position, the drip check 39 will have been raised from the liquid valve tube 37 and the upper extremity of the liquid valve tube will be adjacent the lower portion of the tapering surface of the bottom 45 portion 12. This allows the liquid which has been retained in the measuring cup to flow downwardly through the tube 37 into the bottle 7. The tapering surface of the bottom portion 12 aids the liquid in its travel toward the tube 37 and permits all the liquid in the measuring cup to pass therefrom in a given time.

50 In filling machines of this type, a certain length of time is given for the passing of the liquid from the measuring cup into the bottle. This time remains the same, irrespective of the surrounding temperature and the specific gravity of the syrup. As for instance, a 55 liquid, such as syrup, will flow at a slower

rate of speed during a relatively low surrounding temperature than when the surrounding temperature is relatively high. Some syrups or liquids, owing to their density, require more time to flow from the measuring cup into the bottle than do others. To allow for the slowness of the flow of the liquid during a relatively low temperature, or with the use of a relatively heavy syrup, the body portion 11 may be moved upwardly 70 with respect to the bottom portion 12 by rotating the adjusting nut 33 in a clockwise direction, looking from the top of the adjusting nut. With this adjustment, the measuring cup may be tested to allow the desired four ounces of liquid to pass into the bottle in the limited time. After this adjustment has been made, by removing the set screw 36, the indicating wheel 31 may be reset to register correctly. By again inserting the set screw in place, the indicating wheel 31 may be held in adjusted position. In resetting the indicating wheel, it is obvious that the indicating line adjacent the marking O should be in alignment with the indicating line or groove 30.

55 As the bottle 7 moves downwardly, the measuring cup is also moved downwardly by the force of the compression spring 8, and the drip check 39 engages with the upper 60 end of the liquid valve tube 37 for preventing any liquid which should remain in the tube from passing therefrom until another bottle is brought into alignment with the tube. The drip check 39 is essential when the device 65 is used in a low surrounding temperature or with a heavy liquid for holding all the liquid over four ounces which is received in the measuring cup. If the check 39 is moved out of alignment with the tube 37, the liquid in the tube would continue to flow therefrom.

70 Let us assume that the operator wishes to place three ounces of liquid within the bottle. By rotating the adjusting nut 33 in a counter-clockwise direction, looking from the top of the nut, the sleeve 17 is moved downwardly upon the supporting rod 15, thus moving the body portion 11 downwardly with respect to the bottom portion 12 and decreasing the capacity of the measuring cup 75 to three ounces. The purpose of the graduations 25 upon the cylinder 24 is to indicate to the operator that when the line adjacent the marking 3 oz. has been moved downwardly into alignment with the upper extremity 80 of the collar 22 and the indicating line adjacent the marking O upon the indicating wheel has been brought into alignment with the indicating line 30, the measuring cup will hold 85 just three ounces of the liquid 38. The indicating lines upon the wheel 31 each represent $\frac{1}{32}$ of an ounce. One-half a revolution of the indicating wheel 31 and adjusting nut 33 increases or decreases the capacity of the measuring cup $\frac{1}{8}$ of an ounce, and one whole 90

revolution of the indicating wheel and adjusting nut increases or decreases the capacity of the measuring cup $\frac{1}{4}$ of an ounce. In this manner, the body portion 11 may be moved with respect to the bottom portion 12 so that the measuring cup will receive any desired amount of the liquid 38. It is obvious that with this adjusting means the capacity of the measuring cup may be varied at will from a fraction of an ounce and more. After the body portion 11 has been moved to the desired position with respect to the bottom portion 12, the indicating wheel 31 may be locked against rotation by a screw 40 which is carried by the support 9.

I claim:

1. A device of the type described comprising a tank adapted to hold a liquid, said liquid maintaining a predetermined level in said tank, a liquid valve tube rigidly secured to said tank and having one end extending into said tank to a point above the level of said liquid, the other end of said liquid valve tube to enter a bottle, a measuring cup disposed concentric with said liquid valve tube in said tank, said measuring cup comprising a cylindrical body portion and a tapering bottom portion, a support, a supporting rod rigidly secured at one end to said support, means secured to the other end of said supporting rod for holding said bottom portion of said measuring cup, a sleeve disposed concentric with said supporting rod and movable with respect thereto, said sleeve rigidly secured at one end to said body portion of said measuring cup, an arm rigidly secured to the other end of said sleeve, a post mounted upon said arm and extending through said support, means disposed concentric with said post for moving said post with respect to said support whereby said sleeve may be moved with respect to said supporting rod and said body portion with respect to said bottom portion of said measuring cup, a guide rod extending through said tank and secured at its upper end to said support, means secured to the lower end of said guide rod and adapted to engage with an upwardly moving bottle for moving said measuring cup to a point above the liquid level in said tank, whereby the liquid retained in said measuring cup may flow through said liquid valve tube into the bottle, means disposed concentric with said guide rod for moving said measuring cup downwardly when said bottle has been lowered, and means carried by said support for engaging with said liquid valve tube for preventing any liquid which remains in said tube from passing therethrough while said measuring cup is in the lowermost position.
2. A device of the type described comprising a tank adapted to hold a liquid, said liquid maintaining a predetermined level in said tank, a liquid valve tube rigidly secured to said tank and having one end extending
3. In a device of the type described, a measuring cup comprising a tapering bottom portion, a cylindrical body portion disposed concentric with said bottom portion and movable with respect thereto, means for holding said bottom portion, movable means for supporting said body portion, and means for actuating said movable means for moving said body portion with respect to said bottom portion for varying the capacity of said measuring cup.
4. In a device of the type described, a measuring cup comprising a bottom portion and a cylindrical body portion disposed concentric with said bottom portion and movable with respect thereto, a supporting rod, means secured to said supporting rod for holding said bottom portion, a sleeve disposed concentric with said rod, an arm integral with said sleeve, means secured to said arm for moving said sleeve with respect to said rod whereby said body portion may be moved with respect to said bottom portion of said measuring cup, said means comprising a post secured at one end to said arm and provided with threads, a collar disposed concentric with said post and provided with an internally threaded portion adapted to engage the threads of said post, means for holding said collar against longitudinal displacement, and means disposed concentric with said collar for rotating said collar upon said post.
5. A device of the type described comprising a measuring cup having a body portion, a bottom portion, and means for moving said body portion with respect to said bottom portion, said means including a supporting bar for holding said bottom portion against displacement, and means operatively connected to said supporting bar for moving said body portion with respect to said bottom portion.
6. A device of the type described comprising a measuring cup having a body portion, a bottom portion, and means for moving said

body portion with respect to said bottom portion, said means comprising a supporting bar, means carried by one end of said supporting bar for holding said bottom portion, means arranged to receive the other end of said supporting bar, a sleeve disposed concentric with said supporting bar and movable with respect thereto, said body portion secured to one end of said sleeve, and means operatively connected to the other end of said sleeve for moving said sleeve and said body portion with respect to said bottom portion.

7. A device of the type described comprising a measuring cup having a body portion, a bottom portion, and means for moving said body portion with respect to said bottom portion, said means comprising a supporting bar, means carried by one end of said supporting bar for holding said bottom portion, means arranged to receive the other end of said supporting bar, a sleeve disposed concentric with said supporting bar and movable with respect thereto, said body portion secured to one end of said sleeve, an arm secured to the other end of said sleeve, a post carried by said arm, and means operatively connected to said post for moving said post, said arm, said sleeve and said body portion with respect to said bottom portion.

8. A device of the type described comprising a measuring cup having a body portion, a bottom portion, and means for moving said body portion with respect to said bottom portion, said means comprising a supporting bar, means carried by one end of said supporting bar for holding said bottom portion, means arranged to receive the other end of said supporting bar, a sleeve disposed concentric with said supporting bar and movable with respect thereto, said body portion secured to one end of said sleeve, an arm secured to the other end of said sleeve, a post carried by said arm, means operatively connected to said post for moving said post, said arm, said sleeve and said body portion with respect to said bottom portion, and means disposed adjacent said post for indicating the capacity of said measuring cup.

9. A device of the type described comprising a measuring cup having a body portion, a bottom portion, and means for moving said body portion with respect to said bottom portion, said means comprising a supporting bar, means carried by one end of said supporting bar for holding said bottom portion, means arranged to receive the other end of said supporting bar, a sleeve disposed concentric with said supporting bar and movable with respect thereto, said body portion secured to one end of said sleeve, an arm secured to the other end of said sleeve, a post carried by said arm, means operatively connected to said post for moving said post, said arm, said sleeve and said body portion with respect to said bottom portion, means disposed adjacent said post

for indicating the capacity of said measuring cup, and means arranged to engage with said body portion moving means for holding the movable members in their moved positions.
